(57) CLAIM

The ornamental design for a plush dog, as shown and described.

DESCRIPTION

FIG. 1 is a front elevation view of a plush dog showing our new design;

FIG. 2 is a left side elevation view thereof;

FIG. 3 is a rear elevation view thereof;

FIG. 4 is a right side elevation view thereof;

FIG. 5 is a top plan view thereof; and,

FIG. 6 is a bottom plan view thereof.

The broken lines shown in the drawing are for illustrative purposes only and form no part of the claimed design.

The nose of the dog shown in the drawing is lined for the color red.
